(57) **CLAIM**

The ornamental design for an electrolytic eyepiece, as shown and described.

DESCRIPTION

FIG. 1 is a front right perspective view of an electrolytic eyepiece according to the present invention, where at least a portion of the eyepiece is shown positioned underneath an eyelid of a subject. The dash lines are shown to illustrate environmental aspects of the invention and these portions form no part of the claimed invention.

FIG. 2 is an enlarged front right perspective view of an electrolytic eyepiece according to the present invention.

FIG. 3 is rear right perspective view of the eyepiece according to the embodiment of FIG. 1.

FIG. 4 is a front view thereof.

FIG. 5 is a rear view thereof.

FIG. 6 is a left side view.

FIG. 7 is a right side view thereof.

FIG. 8 is a top view thereof.

FIG. 9 is a bottom view thereof.

FIG. 10 is a front right perspective view of an alternative embodiment of the present invention shown in FIG. 1.

FIG. 11 is rear right perspective view of the eyepiece according to the embodiment of FIG. 10.

FIG. 12 is a front view thereof.

FIG. 13 is a rear view thereof.

FIG. 14 is a left side view.

FIG. 15 is a right side view thereof.

FIG. 16 is a top view thereof; and,

FIG. 17 is a bottom view thereof.

The dash lines are shown to illustrate environmental aspects of the invention and these portions form no part of the claimed invention. Also, the broken lines adjacent to the shaded or sectional portions forms and unclaimed boundary of the design.

1 Claim, 9 Drawing Sheets
